UNITED STATES PATENT OFFICE.

HOWARD S. HART AND LYLE B. MARCY, OF NEW BRITAIN, CONNECTICUT, ASSIGNEES
TO THE HART & COOLEY COMPANY, OF NEW BRITAIN, CONNECTICUT, A CORPORATION OF CONNECTICUT.

TOP PLATE FOR REGISTERS AND VENTILATORS.

1,247,677.

Specification of Letters Patent. Patented Nov. 27, 1917.

Application filed July 31, 1917. Serial No. 183,771.

To all whom it may concern:

Be it known that we, HOWARD S. HART and LYLE B. MARCY, citizens of the United States of America, residing at New Britain, Conn., have invented a new and useful Top Plate for Registers and Ventilators, of which the following is a specification.

Our invention relates to an improved register and ventilator. The object is to provide an improved construction, particularly as to the perforated top plate. By availing of my invention such a plate can be successfully made of very light material with the openings of maximum size, the parts being so constructed and arranged as to withstand heavy weights.

In the drawings:

Figure 1, is a plan view of one corner of a register top plate and associated parts.

Fig. 2, is a view of the under side of a portion of such a plate and associated parts.

Fig. 3, is an end elevation of part of a register.

Fig. 4, is a cross section of the top plate and associated parts.

Fig. 5, is a sectional view partly in elevation of certain parts.

Fig. 6, is a cross section on the line 6—6 of Fig. 1.

Fig. 7, is a perspective view of a detail of the construction.

1 represents the border of a ventilator plate suitable for use as a register top plate.

In such plates it is highly desirable to have openings of as large area as possible so as to permit of the free passage of hot or cold air. To that end we form the plate of sheet metal and punch out suitable air passages 2, 2, 2. The cross bars at the sides of each of the openings are arched in cross-section and the sides or flanges thus formed are folded together, or very close together for the purpose of making all openings of the greatest possible area. At each of the junction points of several cross bars we form pockets 3, 3 on the under side of the plate, said pockets being formed between the depending flanges which continue in a curve around the corners of the openings. 4, 4 are reinforcing beams provided with one or more upwardly projecting lugs 5, 5 so spaced that when a bar 4 is placed on edge underneath the top plate, said lugs 5, 5 will project into said pockets 3, 3 so as to hold the beam 4 in alinement with one of the cross bars of the plate, 55 whereby the beam may not be visible when the plate is viewed from above. The lugs 5, 5 thus pocketed, prevent the lateral deflection or bending of the beam 4 when a load is applied to the top plate. The ends of each beam are of course provided with suitable means for fastening the same in such a position that it will support the perforated part of the top plate when a load is applied thereto. One obvious expedient for supporting the cross beam 4 may comprise a pair of brackets 6, 6 welded or otherwise secured to the under side of the border of the top plate 1. These brackets may have openings into which the ends of the beam 4 may project, 70 which ends are preferably somewhat reduced as at 7, 7 to project into said openings. When the top plate is used in connection with a register it should be provided with one relatively elongated opening 8 to afford 75 clearance for the knob 9 of an operating means for controlling the position of the slats 10, 10. The particular form of this operating means is immaterial but, since it usually includes a slide 11, we preferably cut 80 away one end of each beam 4 as at 12 to afford clearance for said slide 11 or for any parts that may be associated therewith that need clearance space for free movement.

The lugs 5, 5 not only prevent the beam 4 from bending laterally, but they likewise hold the beam from endwise displacement thus making it unnecessary to lock the beam at the ends against endwise displacement. Each beam 4 may be made of substantially 90 the thickness of the two drawn-together flanges of the cross bar under which the beam is located thus gaining a maximum of supporting power without offensive appearance since the beam is hidden by the overlying cross bar of the plate when viewed from above. In the preferred construction of course the lugs 5, 5 should be of such a size as to neatly fit within the respective pockets designed to receive the same at the 95 under side of the junction points of the cross bars.

In the preferred construction the beam 4 is thicker than any space that may be left between the drawn together flanges and yet 105 the displacement of the beam is reliably prevented by the lugs which engage the plate at intervals by projecting into the pockets at

the under side of the junction points of the cross bars. It is obvious that modification may be made without departure from the spirit and scope of our invention.

5. We claim:—

1. In a register plate, a border, a plurality of cross bars extending from edge to edge of said border and crossing each other, the edges of said bars being folded downwardly 10 and close together to form stiffening flanges, relatively enlarged pockets formed by said flanges on the under side of said plate at the junction points of said cross bars, a reinforcing beam supported, at its ends underneath said plate, said beam being arranged edgewise with respect to said plate and in line with one of the bars thereof, the thickness of said plate being greater than the space between the downturned flanges of 15 said cross bar excepting at the junction points, an upwardly extending lug on said beam arranged to project into one of said pockets to hold said beam in alinement with its respective bar and to prevent buckling of 20 said beam when weight is applied on the upper side of said plate.

2. A sheet metal top plate for registers, ventilators and the like, comprising a plate having a border portion and a perforated 30 central portion forming cross bars between said perforations extending from border to border in both directions, said bars being arched in cross-section, the lower part of the sides of said bars being closed together, said 35 cross bars forming pockets on the under side of said plate at the junction points of said bars, a reinforcing beam arranged underneath said plate and having a lug arranged to project into one of said pockets to prevent 40 lateral displacement.

3. A sheet metal top plate for registers, ventilators and the like, comprising a plate having a border portion and a perforated

central portion forming cross bars between 45 said perforations extending from border to border in both directions, said bars being arched in cross-section, the lower part of the sides of said bars being closed together, said cross bars forming pockets on the under side of said plate at the junction points of said 50 bars, a reinforcing beam arranged underneath said plate and having a lug arranged to project into one of said pockets to prevent lateral displacement and longitudinal displacement. 55

4. A sheet metal top plate for registers, ventilators and the like, comprising a plate having a border portion and a perforated central portion forming cross bars extending from border to border in both directions, 60 said bars being arched in cross-section to form side flanges, said flanges being pressed closely together, a reinforcing beam held underneath said plate and edgewise with respect thereto, the thickness of said beam being greater than the space between said flanges, said plate having pockets on the under side at the junction points of said bars, said beam having one or more upwardly projecting lugs projecting into said pockets 65 to prevent buckling of said beam laterally. 70

5. In a top plate for ventilators, a border portion, a perforated central portion formed by cross bars extending from border to border, said cross bars being arched in cross 75 section; the sides of the arched portions being brought closely together, a reinforcing beam with means for supporting the same edgewise at the under side of the plate with inter-connecting means between said plate 80 and bar arranged at intervals in the length of the beam to prevent displacement of said parts when weight is applied to said plate. 85
